(57) **CLAIM**

The ornamental design for a fishing reel body, as shown and described.

DESCRIPTION

FIG. 1 is a perspective view of a fishing reel body showing the new design;

FIG. 2 is a front view of FIG. 1 showing the new design;

FIG. 3 is a rear view of the fishing reel body of FIG. 1 showing the new design;

FIG. 4 is a plan view of the fishing reel body of FIG. 1 showing the new design;

FIG. 5 is a bottom view of the fishing reel body of FIG. 1 showing the new design;

FIG. 6 is a right side view of the fishing reel body of FIG. 1 showing the new design;

FIG. 7 is a left view of the fishing reel body of FIG. 1 showing the new design; and,

FIG. 8 is a perspective view of the fishing reel body of FIG. 1 showing the new design in an environment of use.

The broken lines in the drawings depict environment and portions of the fishing reel body that form no part of the claimed design.

1 Claim, 7 Drawing Sheets
